UNITED STATES PATENT OFFICE.

GEORGE M. BEARD, OF LAGRANGE, INDIANA.

AUTO-TIRE-PROTECTOR JACK.

975,600.

Specification of Letters Patent. Patented Nov. 15, 1910.

Application filed June 6, 1910. Serial No. 565,238.

To all whom it may concern:

Be it known that I, GEORGE M. BEARD, a citizen of the United States, residing at La-
5 grange, in the county of Lagrange and State
of Indiana, have invented a new and useful
Auto-Tire-Protector Jack, of which the fol-
lowing is a specification.

It is the object of this invention to pro-
vide, in a simple, merchantable and inex-
10 pensive form, a vehicle jack which may be
employed to elevate automobiles, provided
with pneumatic tires, so that the automo-
bile, when not in use, may be supported
upon a plurality of these jacks, instead of
15 upon the tires.

Another object of the invention is to pro-
vide a compact jack of the character above
mentioned, and to provide an attachment
20 for such a jack, whereby the jack may be
disposed at different angles with respect to
the vehicle which is to be elevated.

In the drawings,—Figure 1 is a side ele-
vation of the jack in lifting position; Fig. 2
25 is an elevation of the jack showing that side
thereof which is disposed toward the oper-
ator; Fig. 3 is an edge elevation of the jack
when the component parts are disposed
within one another, and longitudinally
30 alined; Fig. 4 is a fragmental perspective
of the inner member or yoke portion of the
jack, showing a removable hook therein;
Fig. 5 is a longitudinal section of the inner
member or yoke, showing the auxiliary hook
35 mounted in place; Fig. 6 is a fragmental
side elevation showing a modification of the
device; and Fig. 7 is a fragmental perspec-
tive, showing a still further modification.

In carrying out the invention, three bail
40 shaped members are provided. The outer
of these bail shaped members, hereinafter
referred to as the support, is denoted by the
numeral 1. The intermediate of these bail
shaped members, acting as a lever, is de-
noted by the numeral 2. The inner of these
45 bail shaped members, hereinafter referred
to as the yoke, is denoted by the numeral 3.
These members 1, 2 and 3 are adapted to
be alined longitudinally, as seen in Fig. 3,
and the construction is such that the inter-
50 mediate member 2 will fit within the outer
member 1, the inner member 3 fitting within
the intermediate member 2.

The lever 2 is pivotally connected, inter-
mediate its ends, with the support 1, as
shown at 4. In the yoke 3 there are a plu-
55 rality of openings 5, adapted to receive a
pin 6 or the like, whereby the yoke may be
connected pivotally to the end of the lever 2.
This pin 6 may be retained in place by
means of cotter pins, as shown, or in any 60
other desired manner.

Adjacent their lower ends, the lever 2
and the support 1 flare laterally, as seen at
7, the yoke 3, however, being a U shaped ele-
ment, the arms of which are parallel. By 65
thus causing the support to flare laterally,
the jack is given a relatively wide support-
ing base, the effective bearing area of the
same being increased by a pair of angle
70 plates 9. One flange of each of which said
plates, is secured to the support, the other
flange thereof being flush with the bottom of
the support. By referring to Fig. 7 of the
drawings, it will be seen that a flat plate
75 30 may be bolted, riveted, or otherwise
secured to the lower portion of the member
1, to replace, when desired, the angle mem-
bers 9. The support 1 is preferably fash-
ioned from channel iron, and the upright
80 flanges of the angle plates 9 are bolted or
otherwise secured to one of the flanges 8
of the support. The lever 2 is of sufficient
length so that when it is moved into aline-
ment with the support 1, the lower end of
85 the lever will abut against the transverse
stop 35, upon the support 1. It is to be
noted that the upper end of the lever 2 is
bent rearwardly to a slight degree, as seen
at 15, so as to hold the lower end of the
lever normally against the stop 35 when the
90 device is in use, and thus maintain the yoke
3 in proper position. This bending of the
lever is not absolutely essential. As shown
in Fig. 6, the same result may be effected
by disposing the openings in the parts 1, 2 95
and 3, slightly out of alinement with each
other, as seen at 25.

The pin 6 may be mounted successively
in the openings 5, in order to adjust the
position of the yoke 3.

One jack is placed adjacent each wheel
of the vehicle, and upon the outside thereof,
the hub of the vehicle wheel being engaged
in the curved portion 11 of the yoke 3,

whereupon the free end of the lever 2 may be depressed, into contact with the stop 35. By this operation the yoke 3 will be elevated, lifting the vehicle off its tires, so 5 that it is supported entirely upon the jacks. When the jack is in operative position, the elements 1, 2 and 3 will be alined, as shown in Fig. 3, thus causing the jack to occupy but a minimum space.

10 A jack constructed as hereinbefore described is adapted to lift a vehicle in situations where there is ample space upon both sides of the vehicle. It may, however, happen that the vehicle is inclosed in a relatively narrow building, so that there will not be room between the hub of the vehicle and the wall of the building for the manipulation of the lever 2. In such case, the lever 2 must be manipulated in a plane parallel to 20 the wheel of the vehicle. In order to meet this situation, I have devised a simple auxiliary hook, the outline of which is seen most clearly in Fig. 4, this hook being adapted to be assembled with the yoke 3. The auxiliary hook consists of a U shaped body portion 10, adapted to fit within the part 11 of the yoke 3. From one end of the body 25 10, a curvilinear finger 12 extends across one edge of the yoke 3; and upon the upper ends 30 of the body portion 10, there are outstanding lugs 14, adapted to engage the opposite edge of the yoke. When this auxiliary hook is mounted in the yoke 3, the hub of the vehicle, or, if desired, the axle thereof, may 35 be engaged in the curvilinear finger 12, whereupon the lever 2 may be operated in a plane parallel to the wheel of the vehicle, the vehicle being thus readily lifted, even when confined within a small space.

40 From the foregoing it will be seen that in order to lift the vehicle under all conditions, it is not necessary to have two separate and distinct sets of jacks. The jack, when disposed as shown in Fig. 1, may be employed 45 for operation at right angles to the plane of the wheel; but should space conditions prevent this operation, the auxiliary hook shown in Fig. 4 may be slipped into the yoke 3, whereupon the jack may be operated in a 50 plane parallel to the vehicle wheel. The auxiliary hook may be fashioned from cast metal at a trifling expense, and by its use, the utility of the jack will be greatly increased.

Owing to the fact that the lever 2 is bail 55 shaped and flared at its free end, as shown at T, the lever will conveniently receive the foot of the operator so that the jack may be worked in that manner.

The inner member 3 of the jack is adapted 60 to receive the hub of the vehicle wheel, to prevent the hub from moving in the jack, parallel to the plane of the wheel of which the hub is a part. From the foregoing, ob-

viously, the member 3 must be relatively narrow. The intermediate member 2 receives 65 the inner member 3, and in order to hold this member 3 against sliding sidewise, the upper end of the member 2 must fit closely about the member 3. By reason of the fact that the member 2 is broadened or flared at its 70 lower end, as denoted by the numeral 7, the foot of the operator may be inserted into the member 2. Thus, although the member 2 at its upper end is adapted to engage the inner member 3 to prevent the same from sliding 75 upon the pin 6, the lower end of the member 2 is wide enough to receive the foot of the operator.

Having thus described the invention, what is claimed is:—

1. A vehicle jack consisting of a bail shaped yoke; and a removable attachment therefor, consisting of a bail shaped body adapted to fit within the yoke, there being a curvilinear finger upon the body depending 85 upon one side of the yoke, and lugs upon the body adapted to interlock behind the other edge of the yoke; a support; and means upon the support for raising and lowering the yoke. 90

2. A device of the class described consisting of three bail shaped members adapted to fit within one another in longitudinally alined relation, the inner of said members being adjustably pivoted to the ends of the 95 intermediate member, and the intermediate member being pivoted between its ends to the outer member; a stop upon the outer member to engage the intermediate member when the members are alined; and a hook 100 adapted to be removably seated in the inner member to project substantially at right angles thereto.

3. A device of the class described comprising three bail shaped members, fitting one 105 within the other, the inner member being adjustably pivoted to one end of the intermediate member and adapted to receive a vehicle hub, the intermediate member being pivoted between its ends to the outer member and constituting a lever for the manipulation of the hub-engaging member; and a bar connecting opposite points upon the outer member to serve as a stop for the intermediate member when the hub-engaging 110 member is elevated.

4. A device of the class described comprising three bail shaped members fitting closely one within the other, the inner member being adjustably pivoted to one end of the intermediate member and being adapted 115 to receive a vehicle hub to hold the same against movement parallel to the plane of the wheel of which the hub is a part, the intermediate member being pivoted between its ends in the outer member, and constitut- 120 125

ing a lever for the manipulation of the hub-
receiving member; the outer member being
flared adjacent its lower end, to broaden the
base of the device, and the intermediate mem-
ber being flared adjacent its lower end to
receive the foot of the operator.

5 In testimony that I claim the foregoing as

my own, I have hereto affixed my signature
in the presence of two witnesses.

GEORGE M. BEARD.
